US00D907935S

(12) **United States Design Patent** (10) Patent No.: **US D907,935 S**
(45) Date of Patent: **** Jan. 19, 2021**

(54) **CHAIR**(71) Applicant: **Steelcase Inc.**, Grand Rapids, MI (US)(72) Inventors: **Nickolaus William Charles Deever**,
Holland, MI (US); **Santiago Carral O'Gorman**, Grand Rapids, MI (US);
Gary Karsten, Wyoming, MI (US)(73) Assignee: **Steelcase Inc.**, Grand Rapids, MI (US)(**) Term: **15 Years**(21) Appl. No.: **29/693,247**(22) Filed: **May 31, 2019**(51) LOC (13) Cl. .... **06-01**(52) U.S. Cl. .... **D6/366**(58) **Field of Classification Search**USPC D6/356, 364, 365, 366, 367, 379, 716,

CLAIM

We claim the ornamental design for a chair, as shown and described.

DESCRIPTION

FIG. 1 is a top front perspective view of a chair;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side elevation view thereof; and,

FIG. 7 is a right side elevation view thereof.

The broken lines shown in the drawings are for the purpose of illustrating portions of the article that form no part of the claimed design.
